UNITED STATES PATENT OFFICE

2,539,703

SINGLE LOCKING WEDGE

Takeo Sato, Honolulu, Territory of Hawaii

Application June 2, 1948, Serial No. 30,562

2 Claims. (Cl. 254—104)

1

This invention relates to a locking wedge device for shoring posts and the like.

It is an object of the present invention to provide a locking wedge device of the character stated comprising a lower member adapted to rest upon the ground, a floor or the like, and an upper member resting upon the lower member and adapted to be secured to the lower end of a shore, post or the like, the contacting faces of the members being inclined and provision being made for the insertion of a pin through a projection on one part, which serves as a guide to prevent lateral displacement of the members one with relation to the other.

Other objects of the present invention are to provide a locking wedge device for shoring posts which is of simple construction, inexpensive to manufacture, easy to apply to the post and to the ground, floor, or the like and efficient in operation.

For other objects and for a better understanding of the invention, reference may be had to the following detailed description taken in connection with the accompanying drawing, in which:

Fig. 1 is a side elevational view of my locking wedging device with the parts thereof connected to the post and to the ground floor or the like and with the pin inserted to retain the wedges in locked positions.

Fig. 2 is an end elevational view of the wedge device,

Fig. 3 is a sectional view taken on line 3—3 of Fig. 1,

Fig. 4 is a top plan view of the wedge device with the upper part removed from the post,

Fig. 5 is a bottom plan view of the upper wedge part,

Fig. 6 is a rear elevational view of the part adapted to be connected to the post,

Fig. 7 is a collective and perspective view of the two wedging parts.

Referring now to the figures, 10 represents a wedging part adapted to rest upon the ground, a floor or the like and having inclined top surface 11 adapted to cooperate with an inclined bottom surface 12 of a top wedging part 13.

The wedging part 10 may be formed of a single piece of strip folded to provide an upright portion 14 and the inclined surface 11. Secured to the center of the inclined surface 11 is a guide portion 15 which extends from one end of the same to the other and prevents the lateral displacement of the parts relative to each other. This guide portion has a series of holes 16 adapted to receive a pin 17 whereby to hold the

2

parts locked together against vertical displacement. The inclined surface portion 11 is supported on partitions 18, 19 and 20 and has a plurality of vertically spaced holes 21 through which a tool bar may be extended to move the part 13 and post 23 on part 10.

The part 13 which is adapted to be connected to a post 23 is formed of a strip of metal which is folded to provide the inclined face portion 12, an upright portion 24 and an attaching portion 25 which lies flush upon the bottom of the post and is secured thereto by fasteners 26 and by fasteners 27 extending respectively through upwardly extending portions 28 and 29.

Through the bottom inclined portion 12 is a slot 31 adapted to receive the projection 15 on the part 10. Large openings 32 are provided in the bottom portion 12 through which a tool can be extended for securing the fasteners 26 in the bottom edge of the post 23. Partitions 34 serve to support the bottom inclined portion 12 of the part 10.

With the part 13 fixed to the post 23 serving as a shoring member and a bar tool extended through the openings 21 the part 13 and post 23 can be worked with the tool upwardly on inclined surface 11 of part 10 to re-position the post.

While various changes may be made in the detail construction, it shall be understood that such changes shall be within the spirit and scope of the present invention as defined by the appended claims.

What is claimed is:

1. A locking wedge device comprising a part 35 adapted to rest on the ground, and having an upwardly inclined top face, a second part having an upwardly inclined bottom face and upwardly extending opposed parallel sides connected thereto that are adapted to embrace a shore post, the inclined facing of the said parts being adapted to cooperate with one another, and the inclined portions of the first part having a longitudinally extending guide projection and the bottom inclined portion of the second part having a longitudinally extending recess that is adapted to receive the projection on the first part, for slidably guiding the movement of the parts on one another, and to prevent lateral displacement of one with respect to the other, and means for locking the parts in their wedged positions, said locking means comprising a series of openings 40 extending along the guide projection of said first part, and a pin extending through one of the openings on the guide projection, and adapted to engage the said second part.

2. A locking wedge device comprising a part adapted to rest on the ground, and having an upwardly inclined top face, a second part having an upwardly inclined bottom face and upwardly extending opposed parallel sides connected thereto that are adapted to embrace a shore post, the inclined facing of the said parts being adapted to cooperate with one another, and the inclined portions of the first part having a longitudinally extending guide projection and the bottom inclined portion of the second part having a longitudinally extending recess that is adapted to receive the projection on the first part, for slidably guiding the movement of the parts on one another, and to prevent lateral displacement of one with respect to the other, and means for locking the parts in their wedged positions, said locking means comprising a series of openings extending along the guide projections of said

first part, through which a pin may be extended to secure the part to the shoring post and the second part having openings through which a tube may be extended to work the post part over the inclined surface of the second part.
